CLAIM

The ornamental design for a one-piece side outlet drain as shown and described.

DESCRIPTION

FIG. 1 depicts an exploded, front, left perspective view of a one-piece side outlet drain shown in an environment of use; FIG. 2 depicts a front elevation view of the one-piece aide outlet drain;

FIG. 3 depicts a rear elevation view thereof;

FIG. 4 depicts a top plan view thereof;

FIG. 5 depicts a bottom plan view thereof;

FIG. 6 depicts a right elevation view thereof; and,

FIG. 7 depicts a left elevation view thereof.

The broken line showing of plumbing hardware which is attached to the one-piece side outlet drain in use in FIG. 1 is for the purpose of illustrating environmental structure and forms no part of the claimed design. All other broken lines are for the purpose of illustrating portions of the one-piece side outlet drain that form no part of the claimed design.

1 Claim, 4 Drawing Sheets
